UNITED STATES PATENT OFFICE.

CHARLES FREDERICK KUSCH, OF CHICAGO, ILLINOIS.

EXIT-DOOR LATCH.

Application filed December 31, 1925. Serial No. 78,501.

This invention relates to an exit door for schools, theaters and the like. It frequently happens in cases of panics in schools, theaters and other public buildings that many lives are lost because of inability to open the exit doors. While the doors may not be locked, yet because of the hysteria of those within trying to get out, no one has the presence of mind to unlatch the door. Oftentimes, too, the press of a mob behind attempting to reach a door will make it impossible for those nearest the door to release the latch.

It is therefore an object of this invention to provide an exit door having a panel on the inside thereof adapted to automatically open the door upon slight pressure there against.

It is a further object of this invention to provide an exit door adapted to be opened automatically when pressure is exerted against any portion of a considerable area of the door.

With these and other objects in view, which will become more apparent in the following description and disclosures, this invention comprises the novel mechanism and combinations hereinafter described and more particularly pointed out and defined in the appended claims.

In the accompanying drawings which illustrate a preferred embodiment of this invention and in which similar reference numerals refer to similar features in the different views.

Figure 1 is an elevational view of an exit door embodying the principles of this invention.

Figure 2 is a sectional view taken on line II-II of Figure 1.

Figure 3 is a sectional view taken on line III-III of Figure 1.

Figure 4 is an elevational view of a modified form of my device.

Figure 5 is a front elevational view of a second modified form of my device.

Figure 6 is a rear elevational view of the same.

Figure 7 is a sectional view taken on line VII-VII of Figure 5.

Figure 8 is a detailed sectional view of a modified form of latching device.

In Figures 1 to 3 inclusive the reference numeral 1 indicates an exit door, embodying the principles of my invention. Said door 1 is provided with the usual hinges 2

adapted to allow the door to open outwardly. On the inside of said door 1 and spaced therefrom, there is pivotally mounted on the brackets 3 a panel 4. Said panel 4 is preferably of relatively large area and extends substantially the height of the door. A sign 5 on the panel 4 indicates that the panel is to be pushed in order to open the door 1. The mechanism for opening said door comprises a bent latching bar 6 secured by bearing lugs 7 to the inner surface of the door 1. Said bar 6 is formed with a pair of horizontal arms 8 and an integral horizontal looped portion 9 intermediate between said arms 8 and extending to the rear edge of the panel 4. An angle shaped member 10 is provided, having one leg secured to the panel 4 adjacent to the rear edge thereof, and the other leg 11 extending horizontally rearwardly into the loop 9. A spring 12 secured at one end to an eyebolt 13 in the door 1 is connected at its other end to the base of the loop portion 9. The ends of the arms 8 are adapted to be retained in sockets 14 on the door jamb 40 when the door 1 is closed.

It will be evident that when the panel 4 is pushed or otherwise swung toward the door 1, as shown in dotted lines in Figure 2, the leg 11 of the angle member 10 will engage the loop 9 to displace the bent latching bar 6 to one side. The arms 8 will thereupon be withdrawn from the sockets 14 and the door 1 will open. When the door is open the spring 12 will act to pull the latching bar 6 back into normal position. In order that the door may be shut more readily, the end of the arms 8 are beveled as at 15 and curved guide members 16 are provided for contacting the beveled ends 15 as the door 1 is swung shut.

In place of the socket 14 I also provide a catch, (Fig. 8), comprising a quarter circular strip 17, having a rounded face 18 over which there extends a guide plate 19. Horizontal arms 20 of the latching bolt are provided with inwardly offset ends 21, adapted to extend behind the strip 17 in normal position. When the panel is pushed, the arms 20 are withdrawn sufficiently to clear the strip 17, and thus allow the door to be opened. In closing the door, the guide plates 19 serve as guides for the ends 21, which are beveled as at 22 to allow them to more easily pass over the curved surfaces of said guides 19. The spring 12 will pull the arms 20 into locked position as soon as

said beveled ends 22 pass beyond the strip 17.

In Figure 4 there is shown a modified form of exit door in which the latching bar 5 is operated in a similar way to that already described, but is brought back into normal position by means of a counter weight instead of the spring 12. There is shown a door 23, a panel 24, pivotally mounted thereon, and a U shaped latching bar 25, operated by said panel. Angle shaped members 26 are provided near the rear edge of said panel 24 for operating the latching bolt 25. As the panel 24 is pushed toward the door 23, said angle members 26 operate to release the latching bolts 25 so that the door 23 may be swung open. A detent member 27, secured to the latching bolt 25 is adapted to be in continuous engagement with an arm 28 of a pivoted unbalanced counter weight 29. On movement of the panel 24, said detent member 27 causes the counter weight 29 to be swung upwardly, but as soon as the door 23 has swung clear of the door jambs, 25 the latching bolt 25 will be free to move back into normal position and this will automatically be accomplished by the falling of the counter weight 29.

In Figures 5 to 7 inclusive I have shown a second modified form of my device illustrating a different method of operating the latching bar. A panel 30 is pivotally mounted adjacent one edge from the inner face of a door 31, as in the previous instances. A plurality of horizontal latching bars 32 are each pivotally mounted at one end on the outside of the door 31 and are supported for limited pivotal movement by yokes 39. Said latching bars 32 are provided at their other ends with rollers 33 adapted to be received in sockets 34 secured to the jamb of the door. A rigid connecting link 38 is secured to said bars 32, so that they all may be operated as a unit. A triangular member 35 is pivotally mounted below one of said bars 32 with its upper horizontal edge contacting the lower edge

of said bar. A cable, or link, 36 is connected at one end to said member 35 by means of a pin 41 extending from said member 35 at a point above its fulcrum through the door 31. Said cable or link 36 is also connected at its other end to an angle member 37. Said angle member 37, like the member 11, is secured to the rear edge of the panel 30, so that when the panel 30 is pushed outwardly, said member 37 draws the link, or cable, 36 to one side and tilts the triangular shaped member 35 as shown in dotted lines in Figure 6. Thereupon the bars 32 are also tilted and their free ends raised out of the sockets 34.

In all the various types of exit doors described, it will be apparent that I have provided means whereby said doors may be readily and quickly opened in case of emergency or panic by persons blindly seeking for a way out.

I am aware that many changes may be made and that numerous details of construction may be varied through a wide range without departing from the principles of this invention, and I therefore do not purpose limiting the patent granted hereon, otherwise than necessitated by the prior art.

I claim as my invention:

1. Bolt mechanism for an exit door, said mechanism including a latching bar, a panel hinged on one edge thereof to said door, and a unitary member on said panel adjacent the hinged edge thereof and engageable with said latching bar to operate the same.

2. Bolt mechanism for an exit door, said mechanism including a unitary latching bar having a plurality of portions thereon engageable with stop members to secure said door, a panel hinged on one edge thereof to said door, and an angular member on said panel adjacent the hinged edge thereof adapted to engage said latching bar to operate the same.

In testimony whereof I have hereunto subscribed my name.

CHARLES FREDERICK KUSCH.
